WARP GOODS

Paul Schönfeld, Chemnitz, Germany

Application October 2, 1937, Serial No. 166,904
In Germany July 16, 1937

3 Claims. (Cl. 66—192)

This invention relates to two-machine plain warp goods with worked in rubber threads.

Various kinds of plain warp goods comprising two thread systems between which rubber warp threads are loosely worked in are known, but a serious drawback of such goods is that the rubber threads which, so to speak, float through the fabric tend to run back. As such warp goods are chiefly used for cutting pieces out of them that are then sewn together to form all kinds of wearing apparel and that have therefore no firm edges, this drawback is exceedingly troublesome. Attempts to fix the rubber threads in position by special arrangement of the two thread systems and mutual binding of the threads have not given satisfactory results hitherto.

According to the invention, the drawback mentioned can be eliminated by repeatedly tying up the rubber threads in the goods so as to form loops.

In this way, the rubber threads can run back only in the space between two loops formed by themselves and are thus practically prevented from running back at all. Pieces can be cut out of such goods without any unpleasant consequences.

By way of example, some forms of the invention are illustrated in the accompanying drawing in which Figure 1 shows a lapping diagram to bring out the composition of the goods, while Figure 2 is a diagram showing several groups of rubber threads.

In Figure 1, the warp goods consist of two thread systems 7 and 8, the thread system 7 representing ordinary ground fabric, such as simple half tricot. The thread system 8 of which only one thread is shown for clearness' sake is worked with overlaying and underlaying operations to form transverse ribs in the ground fabric of the thread system 7. For this purpose, the threads of the group 8 during underlaying operations are alternately racked once in the same direction as the threads of groups 7 and then again in a direction opposite to them. The numerals 1 to 6 indicate the courses in which the racking of the thread group 8 is repeated. The rubber warp threads 9 float between the two thread groups 7, 8 through the goods, but according to the invention are tied up at recurring points 10, i. e. in all six courses shown, by forming meshes in the goods, i. e. the rubber threads are formed into knitted loops by

being fed to the needles at intervals. This is done simply by once overlaying the threads 9 at the points concerned during working of the goods.

The thread groups 7, 8 may be lapped differently than shown. It is immaterial at which distances the rubber threads 9 form loops and how many of these threads are used for the goods.

To produce goods according to the invention the threads of the group 7 are drawn into the lower lapping machine and the threads of the group 8 into the upper machine. The rubber threads 9 are gathered in a machine arranged between two other machines. The thread system 8 produces transverse ribs in a manner described in detail in my co-pending patent application Serial No. 159, 16 399, now Patent No. 2,130,655.

It is further possible to gather the rubber threads 9 subdivided into groups 9 and 9' (Figure 2) into two or more lapping machines. In case of two lapping machines the even numbered 20 rubber threads are guided in one machine and the odd numbered ones in the other. In this way the arrangement may be such that the mesh-forming points of the rubber threads of one group are staggered in the longitudinal direction of the 25 goods relative to the mesh-forming points of the rubber threads of the other group. Then the rubber threads are tied up not in all six courses, as in Figure 1, but in all two times six courses.

The upper lapping machine is the one which is 30 directed toward the needles when the machines are situated upon that side of the needles from which the goods are removed.

I claim:

1. A plain warp knit fabric having two inelastic 35 thread groups and rubber warp threads between the two inelastic thread groups, and being formed into knitted loops in spaced courses only, the upper thread group being worked in without forming knitted loops in those courses in which the 40 rubber warp threads form knitted loops.

2. Warp knit fabric according to claim 1, wherein said upper thread group is shifted sideways only in those courses in which the rubber warp threads do not form knitted loops. 45

3. Warp knit fabric according to claim 1, wherein the rubber warp threads consist of at least two groups which are knitted in the fabric at points staggered in the longitudinal direction in relation to each other. 50

PAUL SCHÖNFELD.
